2,438,556

CIRCUIT FOR ELECTRIC DISCHARGE
DEVICES

Theodorus Hennenkamp, Eindhoven, Netherlands,
assignor, by mesne assignments, to General
Electric Company, Schenectady, N. Y., a cor-
poration of New York

Application February 17, 1943, Serial No. 476,215
In the Netherlands April 6, 1940

Section 1, Public Law 690, August 8, 1946
Patent expires April 6, 1960

3 Claims. (Cl. 315—99)

1

My invention relates to circuits for electric discharge devices, and more particularly to circuits for devices employing filamentary electrodes such as fluorescent lamps.

It is known to connect the series-connection of a serially-connected condenser and a choke coil to a source of alternating current, and to bridge the condenser by the series-connection of another choke coil and a gas-discharge tube, the first-mentioned choke coil, which may also be divided, for example into two portions, and the condenser being so dimensioned that between the terminals of the condenser there is set up a high voltage which ignites the discharge tube.

This device has very satisfactory properties not only as regards the ignition but also the operation of the discharge tube. Thus, for example, it is possible to obtain with this device a very satisfactory power factor which may be even substantially equal to unity. Furthermore, it is easy to obtain the advantage that the higher harmonics produced by the discharge tube can penetrate to the source of current only to a slight extent and that the device is slightly sensitive to the voltage variations occurring in sources of current.

One drawback of this prior art device resides, however, in that upon the closure of the switch with the aid of which the device is connected to the source of current a high voltage is set up across the terminals of the condenser and in other parts of the device even when the discharge tube is not in its holder or holders. At the same time a heavy current passes in this case through the condenser and through the choke coil connected in series therewith. In this case there exists the danger that when one forgets to open the said switch again this high voltage and this heavy current remain in existence, which not only implies an unnecessary loss of energy but also may lead to deterioration of the device.

A further drawback of the known circuit arrangement is seen in that if the discharge tube comprises incandescent electrodes, and if it is desired to heat the latter prior to the ignition of the discharge tube, it is necessary to take particular steps, which complicate the device.

In devices wherein all the auxiliary elements required for the ignition and the operation of the gas-discharge tube are connected in series, these drawbacks may be avoided by incorporating the incandescent electrodes or a conductive bridge provided in the cap or caps of the discharge tube in this series connection so that

2

only the discharge path of the discharge tube is located in parallel with a portion of the series-connection. The properties of these devices differ, however, from those of the first-mentioned device wherein the series connection of a choke coil and a discharge tube is located in parallel with a condenser which in turn is connected in series with another choke coil.

It is, however, impossible directly to modify the last-mentioned device in such manner that all the auxiliary elements are connected in series since in this circuit-arrangement there is a particular point of junction, viz. a point which is connected not only through a choke coil to the discharge tube but also through two branch circuits to the two terminals of the source of current.

A circuit arrangement of this kind which comprises such a point of junction connected through a choke coil to the tube, will hereinafter be shortly referred to as "junction-point system."

Such a junction point also occurs in other devices comprising gas-discharge tubes. It is known, for example, to connect a gas discharge tube in series with a choke coil to a source of alternating current and to mount in parallel with the tube plus the choke coil a condenser which has for its purpose to reduce the phase lag of the current taken from the source of current or even to convert it into a lead. Here again arises the drawback that when a voltage is applied to the device while the discharge tube is not present in the latter, a current flows through the condenser, which means a useless load on the source of current with a greatly leading current. Besides, also in this device the incandescent electrodes which the discharge tube may comprise cannot be heated prior to the ignition without taking particular steps.

A further case wherein such a junction point is present occurs with a device wherein a condenser and a choke coil are connected in series with one another to a source of current and the series-connection of a gas-discharge tube and a choke coil is located in parallel with the first-mentioned choke coil, this choke coil and the condenser being so dimensioned that with the non-ignited discharge tube, due to the saturation of the choke coil which occurs in this case, a very heavy current flows through the circuit and consequently there prevails between the ends of this choke coil a high voltage which ignites the discharge tube whilst after the ignition of the discharge tube the said circuit leaves the tilting state. If a voltage is applied to this de-

vice while the discharge tube is not present a heavy current flows permanently through the condenser and the choke coil due to which they can easily be deteriorated. Furthermore, in this device heating of the electrodes prior to the ignition of the discharge is impossible without further steps.

The invention has for its object to obviate the above-mentioned drawbacks of such devices in which there is a similar point of junction and to retain at the same time the electric properties of these devices.

The device according to the invention corresponds to known junction-point systems in that it comprises a discharge tube which is provided with two bridges which are conductive, at least during the operation of the tube, (which bridges preferably may be constituted by incandescent electrodes or the heating elements of incandescent electrodes, but also, for example, by metal conductors arranged in the caps of the discharge tube or by auxiliary discharges produced between the main electrodes and the corresponding auxiliary electrodes) and each of which comprises two current supply members (A and B, C and D respectively) whilst the member A is connected through a choke coil and, as the case may be, through another impedance to a terminal of a source of alternating current and the member C is connected, as the case may be, through an impedance to the second terminal of this source of current.

According to the present invention, the choke coil comprises an auxiliary winding and the member B is connected through this auxiliary winding and an impedance to the member D, the auxiliary winding being wound in such manner that upon the passage of a series-current through the main winding and the auxiliary winding of the choke coil magnetic fields are generated which counteract one another.

In this device all the auxiliary elements and both conductive bridges present in or on the discharge tube are connected in series so that, when the discharge tube is removed from the holders, the circuit is necessarily interrupted. If the said bridges constitute the incandescent electrodes or the heating elements of the (indirectly heated) incandescent electrodes, these electrodes or their heating elements are directly present in the series-connection formed and they are heated prior to the ignition of the discharge. In this way we obtain the advantages of the series-connection of the auxiliary elements; at the same time, however, owing to the use of the auxiliary winding provided in a particular manner on the choke coil we obtain properties which are absent in the hitherto known devices comprising auxiliary elements connected in series and which correspond to the properties of junction-point systems. This will hereinafter be explained in detail in the description of the form of construction given by way of example.

The choke coil may be, at least partly, bifilarly wound. During normal operation there pass through the two windings in general currents of different intensities. Due to the fact that bifilar winding with wires of different thicknesses requires an excessive winding space, it may be advantageous to constitute the windings by stranded wire of which a determined number of conductors are incorporated in the main winding and the remainder in the auxiliary winding.

By gas-discharge tubes are meant hereinafter not only discharge tubes which are filled with

one or more gases but also tubes which contain a filling of vapour or of a mixture of gas and vapour.

The invention will be explained more fully with reference to the accompanying drawing which represents diagrammatically, by way of example, one embodiment thereof.

In the drawing, 1 denotes a discharge tube serving for the radiation of light, which is constituted by a tube having, for example, a length of 100 cms. and a diameter of 3.5 cms. and which comprises two thermionic electrodes 2 and 3 provided with a substance of high electron-emissivity. The lamp contains a filling of rare gas, for example argon, at a pressure of a few mms. of mercury and, in addition, a small quantity of mercury which exhibits during operation a low-pressure mercury vapour discharge with a positive column. The inner surface of the wall of the tube may be coated with a luminescent substance which is excited to luminescence by the ultra-violet rays generated in the discharge. It is, of course, also possible to utilize in the device according to the invention discharge tubes of other type.

Each of the incandescent electrodes 2 and 3 is provided with two current supply members 4, 5 and 6, 7 respectively which correspond to the above-mentioned members A—D. The member 4 of the electrode 2 is connected through a choke coil winding 8 and a choke coil 9 to the terminal 10 of a source of alternating current whilst the member 6 of the electrode 3 is connected through the intermediary of a switch 11 to the other terminal 12 of the said source of current. If the source of current is constituted by a leakage transformer or by a generator having a high self-inductive reactance, the choke coil 9 may be substituted thereby. The choke coil 9 may also consist of two portions of which the one may be incorporated in the circuit arrangement at the point shown and the other between the switch 11 and the member 6.

The current supply member 5 of the electrode 2 is connected through a winding 13 and a condenser 14 to the member 7 of the electrode 3. The winding 13 constitutes the auxiliary winding of the choke coil of which 8 is the principal winding. The auxiliary winding 13 has been wound in such manner that prior to the establishment of a discharge between the electrodes 2 and 3 the windings 8 and 13 counteract one another.

With the interposition of the heating elements of the incandescent electrodes 2 and 3 the inductive elements 9, 8 and 13 and the capacitative element 14 are connected in series with one another and are so dimensioned that between the electrodes there occurs a voltage which is sufficient for the ignition of the tube. Owing to the fact that the current flowing through this circuit-arrangement raises the electrodes, prior to the ignition, to the temperature of emission, the required ignition voltages acquires a lower value than is the case with a tube comprising cold electrodes.

After the switch 11 has been closed, the magnetic fields generated by the windings 8 and 13 counteract one another so that in the case wherein they have been chosen so as to be mutually equal the voltage supplied to the tube 1 is substantially equal to the voltage across the condenser 14 and, as it were, a short-circuiting connection is produced between the points 15 and 16 of the device. Complete equality of the wind-

ings 8 and 13 is, however, not necessary as experiments have shown.

After the tube 1 has been ignited, neither the intensity nor the phase of the current passing through the winding 13 are in general equal to those of the current flowing through the winding 8. It has been found that there need not exist any appreciable potential difference between the points 15 and 16. Thus we obtain a device which has, so to speak, interconnected points 15 and 16 and, instead of the windings 8 and 13, a single choke coil with all the concomitant good qualities in operation.

By providing the auxiliary winding 13 it is consequently possible to give the device, wherein all the auxiliary elements are connected in series, the properties of a junction-point system without the possibility of giving up pre-heating of the electrode and interruption of the series-circuit upon the removal of the discharge tube from its holders.

It has been found by testing that it is not absolutely necessary to form the winding 13 in such manner and to couple it with the winding 8 so tightly that even when the discharge tube is operating there exists between the points 15 and 16 substantially no potential difference at all. Also in the case of a less tight coupling of the windings 13 and 8, in which event a potential difference of a few tens of volts was set up, between the points 15 and 16, it proved to be possible to obtain, at least to a large extent, the properties of the junction-point system.

In one concrete case the elements of the device had been so chosen that at a mains voltage of 220 volts and 50 cycles prior to the ignition of the tube the joint current passing through all the elements amounted to 0.4 amp., whilst the voltage across each electrode was 12 volts and the voltage between the electrodes was 350 volts. With the tube in operation the current taken from the mains was 0.14 amp., the current flowing through the condenser was 0.225 amp. and the discharge current was 0.25 amp.

The two-wire choke coil 8, 13 was provided with an iron core having an air gap with a cross-sectional area of 3.7 sq. cms. and a length of 0.04 cm. The winding 13 consisted of 1460 turns of copper having a diameter of 0.28 mm. and the winding 8 consisted of 1360 turns with a thickness of 0.2 mm. The winding 13 was arranged around the winding 8. In spite of the fact that the total current passes through the winding 8 it was possible to take for the latter a thinner wire than for the winding 13.

With the tube in operation there occurred across the elements of the device the following voltages: 77 volts across the choke coil 9, 146 volts across the winding 8, 2 volts across each of the incandescent electrodes, 149 volts across the winding 13, 198 volts across the condenser 14 and 103 volts between the electrodes. The potential difference between the points 15 and 16 was in this case 9 volts and the power factor of the device was 0.94 lagging.

Owing to the tight coupling between the windings the potential difference between the points 15 and 16 is slight. It has been found, however, that with a less tight coupling with which the winding 8 and 13 were arranged side by side and there existed between them a leakage field of such intensity that the voltage between the points 15 and 16 increased to 57 volts no appreciable change in the operation of the device occurred.

The application of the invention is, of course,

not restricted to the form of construction given here by way of example. For example, the choke coil 9 may be omitted. Instead of this choke coil there may also be provided a condenser and in this case a choke coil is substituted for the condenser 14. With the use of high saturation this last-mentioned choke coil may also be so dimensioned that, prior to the ignition of the tube, it is tilted over, in co-operation with the condenser which has been substituted for the element 9, into a state of high current intensity but leaves this tilting state when the tube is operating.

The invention may furthermore also be advantageously utilized in order to avoid more than one junction-point. Such is the case, for example, when between the member 6 and the switch 11 there is a choke coil which corresponds to the choke coil 8 and which is provided in this case with an auxiliary winding which is connected between the member 7 and the condenser 14.

In the form of construction described by way of example, the conductive bridges incorporated in the series-connection of the auxiliary elements are formed by the electrodes 2 and 3. The discharge tube may also be provided with two main electrodes, in which event an auxiliary electrode is provided in the neighborhood of each main electrode. The main electrodes are connected in this case to the current supply members 4 and 6 respectively whilst the auxiliary electrodes are brought into connection with the current supply members 5 and 7 respectively. When the device is put into operation, auxiliary discharges are established between each main electrode and the neighbouring auxiliary electrode. These auxiliary discharges, by which the main electrodes are heated, are in series with the auxiliary elements and form the conductive bridges above referred to. Here again the circuit is always interrupted when the discharge tube is not in its holders.

The invention may also be applied when the discharge tube comprises two electrodes which are not heated prior to the ignition of the discharge. In this case the conductive bridges between the members 4 and 5, and 6 and 7 respectively may consist, for example, of two conductors present in the caps of the discharge tube.

What I claim is:

1. In combination, an alternating current supply circuit, an electric discharge device of the type employing an ionizable medium and including a pair of filamentary electrodes each having a pair of terminals, means comprising an inductive choke having a main winding connected in series with one terminal of said source and one terminal of one of said electrodes and an inductively coupled auxiliary winding connected to the other terminal of said electrode, means for connecting the auxiliary winding to a terminal of the other electrode, and means for connecting the other terminal of said other electrode to said supply circuit, said main and auxiliary windings being wound in such manner that upon the passage of series current therethrough opposing magnetic fields are produced.

2. In combination, an alternating current supply circuit, an electric discharge device of the type employing an ionizable medium and including a pair of filamentary electrodes each having a pair of terminals, means comprising an inductive choke having a main winding connected in series with one terminal of said source and one terminal of one of said electrodes and an inductively coupled auxiliary winding connected to the other terminal of said one electrode, a capacitor

connected in series relation with said auxiliary winding and connected to a terminal of the other electrode, and means for connecting the other terminal of said other electrode to said supply circuit, said main and auxiliary windings being wound to produce counteracting magnetic fields upon the passage of series current therethrough.

3. In combination, an alternating current supply circuit, an electric discharge device of the type employing an ionizable medium and including a pair of filamentary electrodes each having a pair of terminals, means comprising an inductive choke having a main winding connected in series with one terminal of said source and one terminal of one of said electrodes and an inductively coupled auxiliary winding connected to the other terminal of said one electrode, a capacitor connected in series relation with said auxiliary

winding and connected to a terminal of the other electrode, and means for connecting the other terminal of said other electrode to said supply circuit, said main and auxiliary windings being bifilarly wound and consisting of stranded wire of which a predetermined number of conductors are incorporated in the main winding and the remainder in the auxiliary winding.
